UNITED STATES PATENT OFFICE

160,514

WHEEL COVER OR SIMILAR ARTICLE

George Albert Lyon, Detroit, Mich.

Application June 28, 1949, Serial No. 3,607

Term of patent 14 years

(Cl. D14—30)

To all whom it may concern:

Be it known that I, George Albert Lyon, a citizen of the United States, and a resident of the city of Detroit, in the county of Wayne and State of Michigan, have invented a new, original, and ornamental Design for a Wheel Cover or Similar Article, of which the following is a specification, reference being had to the accompanying drawing, forming a part thereof.

On the drawing:

Figure 1 is a side view of my novel design of wheel cover;

Figure 2 is a profile view showing the cross-sectional shape of the cover; and

Figure 3 is a fragmentary perspective view of the cover.

The dotted line showing in the drawing figures is for illustrative purposes only.

I claim:

The ornamental design for a wheel cover or similar article, substantially as shown and described.

GEORGE ALBERT LYON.
